UNITED STATES PATENT OFFICE.

WILLIAM T. BENHAM, OF NORWOOD, AND JOHN E. DWYER, OF CINCINNATI, OHIO,
ASSIGNORS TO THE HALL'S SAFE COMPANY, OF CINCINNATI, OHIO, A CORPOR-
ATION OF OHIO.

TIME-LOCK MECHANISM.

Application filed May 16, 1924. Serial No. 713,771.

This invention relates to time lock mechanism employable in safes, including vaults and the like, hereinafter designated safes.

It is the object of the invention to provide novel means whereby the holding means for the bolt control is held in holding relation by oppositely movable parts so that shocks or jars tending to move one of said parts in a given direction will also tend to move an oppositely movable part in the opposite direction for maintaining the holding effect of said holding means; further, to provide oppositely movable control parts for the holding means movable in opposite directions for effecting the positioning of the holding means; further, to so interconnect said control parts that movement of one of them in a given direction will cause movement of another of them in the opposite direction; further, to provide oppositely movable holding parts movable in opposite directions for effecting the holding of a bolt-works element to maintain the bolt-works in locked relation; and the invention will be further readily understood from the following description and claims, and from the drawings, in which latter:

Fig. 1 is a rear elevation of a portion of a safe-door, showing the present invention applied thereto, with the door of the time casing partly broken away for exposure of the interior of the casing, and showing the holding parts in holding relation.

Fig. 2 is a similar view, partly broken away, showing the holding means in release relation.

Fig. 3 is a vertical cross-section of the same, taken in the plane of the line 3—3, of Fig. 1, partly broken away.

Fig. 4 is a cross-sectional detail, taken on the section line 4—4, of Fig. 1, showing the mounting of the exemplified bolt-control part.

Fig. 5 is a cross-section of the same, taken on the line 5—5, of Fig. 1, and showing the releasable pinion and handle in position.

Fig. 6 is a detail in cross-section, taken on the irregular line 6—6, of Fig. 1, showing the holding means and the control means for the same, partly broken away.

Fig. 7 is a cross-section of the same, taken in the plane of the line 7—7, of Fig. 6.

Fig. 8 is a detail in cross-section, taken on the line 8—8 of Fig. 1; and,

Fig. 9 is a detail in cross-section, taken 55 on the line 9—9, of Fig. 1.

The door of the safe is exemplified at 11. The door may be that of any suitable safe of any ordinary or usual construction, such as a burglar-proof safe, having an integral 60 body, or a body comprising steel plates, or be a vault body, or of other suitable structure. The door may be a so-called round door, or the door may be of other suitable form or other desirable structure. 65

Any suitable bolt-works may be employed in connection with the door for locking the same, and may comprise any suitable control means for maintaining the same in locked relation. We have exemplified only a portion 70 of such bolt-works as a slide 12, instanced as a control-part of the bolt works, although this control-part may be of any other desirable structure or have any other desirable movement. We have exemplified 75 this control-part as having slots 13, through which shoulder-bolts 14 extend, the shoulder bolts being threaded into the door.

The control-part has an arm 17 extending therefrom, by means of which the control-part is arranged to be held by the time lock mechanism, the release of said control-part preferably being such as to cause movement thereof to release the bolt-works or permit the bolt-works to be manipulated for 85 opening the door.

The time lock mechanism comprises a casing 21, which is secured to the door by screws 22, received through the rear wall of the casing and threaded into the door, resilient 90 washers 23, for instance of rubber, being located between the casing and such rear wall to cushion the time mechanism in order to avoid detrimental effect thereon by shocks or jars to which the safe or the door may 95 be subjected.

The casing is provided with a door 25, closed or locked in suitable manner, and having a transparent insert 26 therein, through which the dials of the time mechanism may 100 be viewed.

The holding means for the slide are exemplified as comprising oppositely acting latches 27, 28, shown located on levers 29, 30, provided with pivot-flanges 31, 32. These 105 pivot-flanges rotate about a stud 33 of a stud-piece 34. A screw 35 passes through a washer 36 and the stud-piece, and is

threaded into a hanger 37 of a plate 38 for holding the washer, the stud-piece and the plate securely together, and permitting swinging of the levers about the stud-piece.

5 The pivot-flanges are shown reduced in thickness with relation to the latches, so as to place the latches in the same plane. The lever 29 comprises an arm 41, and the lever 30 comprises an arm 42.

10 The plate 38 is secured to the inside of the wall 43 of the casing. The bottom wall 44 of the casing is provided with a slot 45, through which said hanger and said levers extend.

15 The arms 41, 42, have articulations 47, 48, with lugs 49, 50, on oppositely movable bars 51, 52, so arranged that movement of one bar in one direction effects movement of the articulated end of the lever articulated

20 therewith in the same direction, and movement of the opposite bar and the articulated end of the other lever in opposite direction. The articulations 47, 48, each comprise a pin 53 fixed to the arm and received in a slot 54

25 in the bar, in order to compensate between the relative arcuate movement of the arm and the right line movement of the bar.

The opposed movements of the bars are effected in the present instance by providing 30 disks 56, 57, rotatable on shoulder screws 58, 59, secured to the plate 38, and providing the disks respectively with pins 61, 62. The pins 61 are located in holes 63 of the bar 52,

35 and the pins 62 are located in holes 64 in the bar 51. The respective pins are on opposite sides of the disk, so that rotation of the disks in either direction moves the bars lengthwise in opposite directions. Each of the disks is provided with a spacing-hub 65,

40 and the bars are positioned in the space between the disks and the plate 38, respectively above and below the hubs.

The means exemplified for actuating the bars is a time mechanism, consisting of a 45 series of time-clocks 71, 72, 73, such as are used in time lock devices in safes. The time-clocks are provided with dials 74, having thereon knock-out pins 75. The dials are provided with suitable graduations of a suitable number of hours, for instance seventy- 50 two hours, and are arranged to be set and to be rotated by suitable clock movements therein, which may be wound in suitable manner, not necessary to be further described as the same are well-known.

Suitable hands 76 are provided, with relation to which the dials are rotated to indicate the number of hours to expire before the time mechanism is moved into releasing 60 relation, and at which the safe is to be opened. The releasing movement is effected by any one or more of the pins 75, coating with one of the bars concerned in effecting release of the holding means for the bolts.

65 The spring of any one of the time move-

ments is of sufficient strength to cause such release, so that such release may be effected if only one of the time devices remains in working condition, although ordinarily all of the time devices combine to effect such 70 movement.

The movement of the bars is exemplified as effected by means of levers 78, pivoted on shoulder-screws 79, one end of the levers being within range of the pins on the respective dials, and the other end of the levers being within range of shoulders 80, shown as the end walls of slots 81 in the bar 52, in which said other ends of said levers are received.

The latches are normally urged into latching relation by means of a spring 82, received about a pin 83, fixed to a lug 84, extending from the plate 38, the spring being located between said lug and a lug 85 fixed to the bar 51, for normally urging the bars in directions to effect holding positions of the latches.

The slide 12 is represented as normally retracted by a spring 86 for release relation of the bolt-works, the respective ends of the spring being secured to said slide and to the safe-door. The slide has a rack 87 with which a pinion 88 meshes, the pinion rotating on a stud 89 extending from the safe-door. The pinion is releasable from the stud and is provided with a handle 90 for rotating the same.

When it is desired to lock the safe, the time-clocks are wound and the disks turned to set the same for the beginning of the period of locked relation of the door, whereby the knock-out pins are spaced from the knock-out levers, as shown in Fig. 1. The latches are thereby also placed in engaging 105 positions. The slide 12 is then moved for placing its holding arm 17 in latching relation with the latches, which is effected by movement of the slide by means of the pinion 88. The engaging portion of the arm is provided with a sloping face 92 coating with the sloping faces 93 of the latches for ready reception of the arm above the hooks of the latches. The door may now be closed and locked, and will remain locked throughout the time for which the time-clocks have been set. At the expiration of such time, the knock-out pins of the time-clocks will actuate the knock-out levers, for operating the bars in opposite directions, and operating the latches in opposite directions, for release of the bolt-works through the medium of the control-part or slide 12.

If the safe or the door or the timing mechanism should, during such locked relation, be subjected to any shock or jars, it will be readily seen that any shock or jar tending to move any part of the time-lock control means for the bolt-works in one direction will also tend to move an opposite 130

part of said control means in the opposite direction, insuring a holding relation of the bolt-works control throughout the locked relation of the safe. Any shock or jar which 5 might tend to create an unlocking movement in one of the opposing parts, either in the holding means or in the actuating means therefor, is transmitted as a shock or jar in locking direction upon the corresponding 10 opposing part. The elements of the pairs of opposing parts act as opposing elements movable in opposite directions for maintaining a locked relation of the bolt control mechanism.

15 The danger of effecting opening of the door or release of locking relation in any of the mechanism is, therefore, minimized or avoided.

Having thus fully described our invention, what we claim as new, and desire to secure by Letters Patent, is:

1. In time lock mechanism, the combination of clock mechanism, a bolt-works part, oppositely movable connected operating parts, said clock mechanism comprising means for automatically operating said connected operating parts, and holding means for said bolt-works part, said oppositely movable operating parts having operative 25 connection with said holding means, said oppositely movable operating parts movable in opposite directions for automatically actuating said holding means for release relation in said holding means.

30 2. In time lock mechanism, the combination of clock mechanism, a bolt-works part, oppositely movable holding parts for said bolt-works part, oppositely movable operating parts for said oppositely movable holding parts, means connecting said oppositely movable operating parts with said oppositely movable holding parts respectively, and means connecting said oppositely movable operating parts for combined movements 35 thereof in opposite directions, said clock mechanism comprising means for automatically operating said operating parts.

3. In time lock mechanism, the combination with time mechanism and a bolt-works 40 part, of oppositely movable latches for holding said bolt-works part, bar means comprising bars having operative connection with said latches, connecting means between said bars to cause opposite movements of 45 said bars, and operating means between said time mechanism and said bar means.

4. In time lock mechanism, the combination of a time-clock casing, time-clocks mounted therein, bar means comprising op-

positely movable bars in said casing, oppositely movable latches having operative connections with said bars, said latches arranged for coaction with a bolt-works part, means normally urging said latches into latching relation, and operative connecting 65 means between said time-clocks and said bar means.

5. In time lock mechanism, the combination of a time-clock casing comprising a wall, time-clocks mounted therein, oppositely movable bars, disks pivoted to said wall connecting said bars, said bars guided between said wall and said disks, levers between said time-clocks and one of said bars, 70 latches pivoted to said time-clock casing and having articulations with said bars respectively, and a bolt-works part arranged for coaction with said latches.

6. In time lock mechanism, the combination of a time-clock casing comprising a wall, time-clocks mounted therein, oppositely movable bars, disks pivoted to said wall connecting said bars, said bars guided between said wall and said disks, levers between said time-clocks and one of said bars, 75 means normally retracting said bars, latches pivoted to said time-clock casing and having articulations with said bars respectively, and a bolt-works part arranged for coaction with said latches.

7. In time lock mechanism, the combination with a time-clock casing, time-clocks mounted therein, said casing having a wall, oppositely movable bars, disks pivoted to said wall having articulations with said bars respectively, said bars guided between said wall and said disks, latch levers pivoted to said casing and having articulations with said bars respectively, said casing having a lower wall provided with a slot 95 through which said latches extend, and means normally moving said latch levers into latching relation, said latch levers arranged for coaction with a bolt-works part.

8. In time lock mechanism for a safe door, the combination with a time-clock casing on the door, time-clocks mounted therein, oppositely movable bars in said casing, oppositely movable latches having operative connections in said casing with said bars 100 respectively, said latches extending outside said casing for co-operation with bolt mechanism, and operative connections between said time-clocks and said bars.

In testimony whereof, we have hereunto 115 signed our names.

WILLIAM T. BENHAM.
JOHN E. DWYER.
